E. WEINTRAUB

BUCKLE

Filed May 15, 1924

INVENTOR

EDWARD WEINTRAUB
BY
O. D. Edwards
ATTORNEY

UNITED STATES PATENT OFFICE.

EDWARD WEINTRAUB, OF NEW YORK, N. Y.

BUCKLE.

Application filed May 15, 1924. Serial No. 713,876.

To all whom it may concern:

Be it known that I, EDWARD WEINTRAUB, a citizen of the United States, and a resident of Brooklyn, county of Kings, and State of New York, have invented a new and useful Improvement in Buckles, of which the following is a specification.

The object of my invention is to provide a simple, light, efficient and durable buckle which will hold a strap firmly in any desired position, without the action of any moving parts. This and other objects are accomplished by my invention, one embodiment of which is hereinafter more particularly set forth.

For a more detailed description of my invention, reference is to be had to the accompanying drawings, forming a part hereof, in which—

Figure 1 is a front elevation of my improved buckle when in use.

Figure 2 is a sectional view of the same, taken on the line 2—2 of Figure 1.

Figure 3 is a front view of the buckle separated from the strap.

Figure 4 is a sectional view, taken on the line 4—4 of Figure 3.

Throughout the various views of the drawings, similar reference characters designate similar parts.

My improved buckle 1 is composed of two longitudinal side pieces 2 united by four crossings 3, 4, 5 and 6 respectively. The crossings 3 and 6 have laterally extending

flanges 7 at their inner ends and the crossings 4 and 5 have inwardly extending teeth 8 at their inner edges so that they may grip the strap 9, as shown in Figure 2.

From this figure, it appears that the end 10 of the strap is wrapped around the outer face of the crossing 5 and thence over and between the crossings 4 and 5 and against the teeth which grip the same and thence back over the crossing 4 and crossing 5 and between this crossing and the crossing 6 to the loop 11 which may go round any desired object or any part of a person, and thence the strap runs over a flange 7 and between the crossings 3 and 6 and over the crossings 4 and 5 and thence over the flange 7 on the crossing 6 and between this crossing and the crossing 5. The strap may be readily adjusted with regard to the buckle and the buckle will hold in any desired position.

Having thus described my invention, what I claim is:

A buckle having side flanges united by crossings, the two outer crossings having at their inner edges laterally extending flanges and two intermediate crossings between the outer crossings having at their inner edges inwardly extending teeth.

In testimony whereof, I have hereunto set my hand and seal this 10th day of May, 1924.

EDWARD WEINTRAUB.
